UNITED STATES PATENT OFFICE.

HENRY LEWIS GAUGHAN, OF HAMILTON, OHIO.

HEADLIGHT.

Application filed December 17, 1925. Serial No. 76,017.

The present invention relates to headlights for automobiles and the like.

One of the principal objects of the invention is to provide a headlight so constructed and arranged as to eliminate the glare from the lighting element, so that the beam of light projected from the headlight will not blind drivers of automobiles and pedestrians approaching in the opposite direction.

10 Other and further objects of the invention will appear from the following description in connection with the accompanying drawing in which:—

Fig. 1 is a front view of the headlight embodying the invention; and

Fig. 2 is a vertical cross sectional view taken on the line 2—2 of Fig. 1.

As illustrated the headlight comprises an outer casing 10 which may be of any suitable 20 or convenient shape and which may be provided with fastening means 11 by which the headlight may be fastened to a vehicle.

25 Mounted within the casing 10 is a reflector element 15. The lighting element or light source is indicated at 16 and may be of any usual form such as an incandescent lamp. The lighting element is positioned in the upper part of the reflector element and that portion of the latter which is below the horizontal plane passing through the light source is given a shape resembling generally the half 30 of a paraboloid, although it will be understood that this portion of the reflector may be of any other suitable shape. Above the horizontal plane of the light source the reflector element is formed to provide a dome 17 the forward part of which comes down as at 18 to substantially the horizontal plane of the light source in order to intercept the direct rays of the light source above the horizontal plane and prevent glare from the direct rays of the light source. The dome portion of the reflector element is preferably polished internally so as to reflect the rays above 40 the horizontal plane of the light source downwardly to the ground and to the paraboloid portion of the reflector which in turn reflects the light forwardly to produce the desired illumination.

50 I have discovered that a glare may come from that portion of the reflector element which is immediately back and to the rear of the lighting element 16, and I have therefore provided what is termed a blind spot in the reflector element to prevent glare from this part of the reflector element. In the pre-

ferred construction the blind spot is produced by cutting away a part of the reflector element so as to provide an opening 22 incapable of reflecting, but it should be understood that the blind spot may be produced in any other suitable manner as, for example, by modifying the character of this part of the reflector surface, the requirement being merely that no glare shall be produced from this area of the reflector.

The upper forward part of the reflector element may be turned outwardly as at 19 so as to form with the remainder of the reflector element a circular attaching edge by which 70 the reflector element may be secured in position within the casing 10.

The source of light or lighting element 16 may be supported in any convenient manner. In the construction illustrated I take advantage of the opening formed by the blind spot 22 to project therethrough the socket or support 20 for the lighting element, such socket being mounted upon a lip 21 inturned from or otherwise secured to the casing 10. It is 80 apparent that the socket for the lighting element need not project through the blind spot but may be passed through the wall of the dome portion 17 of the reflector element.

From the foregoing it will be apparent that 85 the present invention utilizes nearly all of the light radiating from the light source to produce a beam of light. The reflector element is preferably so formed as to illuminate the roadway far in advance of the vehicle 90 without producing upward glare, that is,—without projecting substantially any light above a horizontal plane passing through the region of the light source, and at the same time to produce a distributed illumination of 95 the intermediate portion of the roadway. It should be understood that the words "horizontal," "upward," and other words indicating direction, as used in the specification and claims are not used in a limiting sense but merely for convenience in referring to locations and directions relative to the headlight.

100 While the form of apparatus herein described constitutes a preferred embodiment of the invention, it is to be understood that the invention is not limited to this precise form of apparatus, and that changes may be made therein without departing from the scope of the invention which is defined in the appended claims.

110 What is claimed is:

1. A headlight comprising a casing, a light

source, a reflector member mounted within said casing, said reflector member comprising a downwardly and forwardly extending reflecting portion below the light source, and an upwardly and forwardly curved portion above the light source, and a depending and rearwardly reflecting portion in advance of the light source to intercept the direct rays of light radiating forwardly and above the horizontal plane of the light source, an in-turned lip portion connected with said casing, a mounting for said light source carried by said lip portion, and a blind spot in said reflecting member located below and to the rear of said light source, said blind spot being an opening in the reflector member receiving the mounting for said light source.

2. A headlight comprising a light source, a reflector member for said light source, said reflector member including a downwardly and forwardly extending reflecting portion below the light source, an upwardly and forwardly curved reflecting portion above the light source, and a depending reflecting portion in advance of the light source for intercepting the direct rays of light radiating forwardly and above the horizontal plane of the light source, said reflecting portion above the light source and said depending portion in advance of the light source serving to reflect the rays of light radiating above the horizontal plane of the light source downwardly to the ground to increase the illumination of the headlight, and a blind spot in said downwardly and forwardly extending reflecting portion below and to the rear of said source of light for preventing glare from said reflecting surface, the upper extremity of said

blind spot being located substantially adjacent the horizontal plane of the light source, 40 whereby the reflecting portion above the horizontal plane of the light source remains effective to increase the illumination of the headlight.

3. A headlight comprising a light source, a 45 mounting therefor, a reflector member for said light source, said reflector member including a downwardly and forwardly extending reflecting portion below the light source, an upwardly and forwardly curved 50 reflecting portion above the light source, and a depending reflecting portion in advance of the light source for intercepting the direct rays of light radiating forwardly and above the horizontal plane of the light source, said 55 reflecting portion above the light source and said depending portion in advance of the light source serving to reflect the rays of light radiating above the horizontal plane of the light source downwardly to the ground to increase the illumination of the headlight, and a blind spot in said downwardly and forwardly extending reflecting portion below and to the rear of said source of light for preventing glare from said reflecting surface, the 60 upper extremity of said blind spot being located substantially adjacent the horizontal plane of the light source, whereby the reflecting portion above the horizontal plane of the light source remains effective to increase the illumination of the headlight, said blind spot being an opening in the reflector adapted to receive said mounting for the light source. 65

In testimony whereof I hereto affix my signature.

HENRY LEWIS GAUGHAN.
